UNITED STATES PATENT OFFICE.

ANST ALEXANDER AND ARNOLD M. STEINBERG, OF PARIS, TENNESSEE.

DESIGN FOR A BOTTLE.

44,867.

Specification for Design.

Patented Nov. 11, 1913.

Application filed August 27, 1913. Serial No. 787,032. Term of patent 7 years.

To all whom it may concern:

Be it known that we, ANST ALEXANDER, a subject of the King of Bulgaria, and ARNOLD M. STEINBERG, a citizen of the United States, and residents of Paris, in the county of Henry and State of Tennessee, have invented a new, original, and ornamental Design for Bottles, of which the following is a specification, reference being had to the accompanying drawing, forming part thereof.

Figure 1 is a front view of the bottle

illustrating our new design; Fig. 2 is a plan view thereof; and Fig. 3 is a side view thereof.

We claim:

The ornamental design for a bottle, as shown.

ANST ALEXANDER.
ARNOLD M. STEINBERG.
